BOTTLE OR THE LIKE

Dean R. Straka, Evansville, Ind., assignor to Mead Johnson and Company, Evansville, Ind., a corporation of Indiana

Filed Oct. 14, 1966, Ser. No. 4,287

Term of patent 14 years

(Cl. D58—6)

FIG.3

FIG.4

FIG. 1 is a front elevational view of a bottle or the like showing my new design;

FIG. 2 is a side elevational view thereof;

FIG. 3 is a top plan view thereof; and

FIG. 4 is a bottom plan view thereof.

The side of the bottle opposite that shown in FIG. 2 is substantially identical with that shown.

The rear of the bottle is substantially identical with the front thereof shown in FIG. 1.

I claim:

The ornamental design for a bottle or the like, substantially as shown and described.
